Attorney

UNITED STATES PATENT OFFICE

WALTER GALETSCHEKY, OF PITTSFIELD, MASSACHUSETTS

SODA STRAW ATTACHMENT

Application filed February 14, 1930. Serial No. 428,406.

This invention relates to an attachment into a neck 5 provided with an outwardly offset shoulder forming portion 6 and terminating in a flared sleeve 7 adapted for the reception of the lower end portion of the soda straw 8. The soda straw 8 is of the usual waxed paper construction but the same may be of any suitable material and forms no part of this invention. The lower end of the soda straw 8 is adapted to rest on the shoulder provided by the offset portion 6 in the neck 5 to limit the inward movement of said soda straw.

Another important object of the invention is to provide an attachment for soda straws of the character set forth which may be expeditiously mounted on or removed from conventional straws such as are in widespread use at present.

Other objects of the invention are to provide an attachment for soda straws of the aforementioned character which will be simple in construction, strong, durable, efficient in its use and which may be manufactured at low cost.

All of the foregoing and still further objects and advantages of the invention may become apparent from a study of the following specification, taken in connection with the accompanying drawings, wherein like characters of reference designate corresponding parts throughout the several views, and wherein:

Figure 1 is a view in elevation showing an attachment constructed in accordance with this invention mounted in position on the end portion of a soda straw and disposed in a glass of liquid.

Figure 2 is an enlarged view in side elevation of the device mounted in position on the straw, the lower end portion only of the latter being shown.

Figure 3 is a vertical sectional view taken substantially on the line 3—3 of Figure 2.

Referring to the drawings in detail, the reference character 1 designates a conical valve casing formed of any suitable material, preferably thin metal, having a valve seat 2 in its lower end from which extends an inlet neck 3 which is of uniform diameter throughout.

The upper end portion of the valve casing 1 is provided with an inwardly tapering shoulder forming portion 4 which merges

55 for soda straws and has for its primary object to provide, in a manner as hereinafter set forth, a device of this character which will prevent a liquid which has been drawn into the straw from receding therefrom back into the glass or other receptacle when the person drinking said liquid stops drawing on the straw.

60 10 Another important object of the invention is to provide an attachment for soda straws of the character set forth which may be expeditiously mounted on or removed from conventional straws such as are in widespread use at present.

65 Other objects of the invention are to provide an attachment for soda straws of the aforementioned character which will be simple in construction, strong, durable, efficient in its use and which may be manufactured at low cost.

70 All of the foregoing and still further objects and advantages of the invention may become apparent from a study of the following specification, taken in connection with the accompanying drawings, wherein like characters of reference designate corresponding parts throughout the several views, and wherein:

75 Figure 1 is a view in elevation showing an attachment constructed in accordance with this invention mounted in position on the end portion of a soda straw and disposed in a glass of liquid.

80 Figure 2 is an enlarged view in side elevation of the device mounted in position on the straw, the lower end portion only of the latter being shown.

85 Figure 3 is a vertical sectional view taken substantially on the line 3—3 of Figure 2.

Referring to the drawings in detail, the reference character 1 designates a conical valve casing formed of any suitable material, preferably thin metal, having a valve seat 2 in its lower end from which extends an inlet neck 3 which is of uniform diameter throughout.

90 The upper end portion of the valve casing 1 is provided with an inwardly tapering shoulder forming portion 4 which merges

95 for soda straws and has for its primary object to provide, in a manner as hereinafter set forth, a device of this character which will prevent a liquid which has been drawn into the straw from receding therefrom back into the glass or other receptacle when the person drinking said liquid stops drawing on the straw.

100

terial to be destroyed after the same has been used once.

The valve 9 may be in the form of a candy ball if it is so desired. This invention also 5 contemplates a check valve constructed in accordance with this invention formed as an integral part of the soda straw instead of being detachable and a separate part therefrom.

10 While the invention has herein been described for use in association with soda straws, it is understood that the same may be utilized for any purpose for which it may be found adapted such as for use in pipettes.

15 It is believed that the many advantages of a soda straw attachment constructed in accordance with this invention will be readily understood, and although the preferred embodiment of the invention is as illustrated

20 and described, it is to be understood that changes in the details of construction may be had which will fall within the scope of the invention as claimed.

What is claimed is:—

25 1. An attachment for soda straws of the character described comprising a metallic tapered valve casing, an integral inlet neck on one end of the valve casing, said neck being of less diameter than said casing and 30 having one end formed to provide a valve seat, a ball check valve loosely disposed for movement in the casing and engageable on the seat in a manner to control the passage through the inlet neck, and an integral flared 35 sleeve on the other end of the casing for the reception of the soda straw for detachably mounting the valve casing thereon.

2. An attachment for soda straws of the character described comprising a valve casing, said valve casing being provided with a liquid inlet on one end, a ball check valve loosely disposed in the casing and adapted 40 to control the inlet passage, a sleeve formed integrally on the opposite end of the casing 45 for the reception of the soda straw for mounting the casing thereon in communication therewith and integral abutments struck inwardly from the side walls of the casing for engagement with the ball check valve in 50 a manner to limit the upward movement of the same in the casing.

3. An attachment for soda straws of the character described comprising a valve casing having a tapered body portion, an integral flared sleeve extending from the tapered body portion for slidably receiving one end 55 of the soda straw for mounting the valve casing thereon in communication therewith, an annular shoulder on the inner end of the 60 sleeve for engagement with the end of the soda straw, said shoulder constituting a stop therefor, integral abutments struck inwardly from the tapered upper portion of the valve body for engagement with the ball valve in 65 a manner to limit the upward movement of

the same in the casing, a valve seat in the opposite end of the casing for the reception of the ball valve and an inlet neck extending from the casing and communicating therewith.

70 In testimony whereof I affix my signature.

WALTER GALETSCHKY.
